UNITED STATES PATENT OFFICE.

EDWARD P. STRODE, OF NEW YORK, N. Y.

PACKING-TOOL.

973,146.

Specification of Letters Patent. Patented Oct. 18, 1910.

Application filed March 4, 1910. Serial No. 547,324.

To all whom it may concern:

Be it known that I, EDWARD P. STRODE, a citizen of the United States, and resident of New York, borough of Manhattan, county 5 and State of New York, have made a new and useful invention in Packing-Tools, of which the following is a specification.

My invention is directed particularly to improvements in packing tools designed for use in connection with condensers in power plants, where the opposite ends of condenser tubes are secured in tube sheets and stranded packing is forced into position in grooves in the tube sheets around the outer ends of such tubes, and it has for its object, to provide a power actuated packing tool which quickly and effectually produces the desired result.

My invention will be fully understood by referring to the accompanying drawings, in which,

Figure 1 represents in longitudinal sectional view my improved packing tool and the manner of using the same, a partial sectional view of the tube sheet and one of the tubes being illustrated and the packing shown in position, the operating trigger of the tool being shown in side elevational view. Fig. 2 is a detail sectional view illustrating a 20 part of a tube sheet and a tube, together with the packing secured in position between the two by a tubular set-nut in the usual way. Fig. 3 is an end view as seen looking at the barrel portion of the tool shown in Fig. 1 from left to right. Fig. 4 is a detail side elevational view of the outer end of the barrel portion. Fig. 5 is a detail side elevational view of that part of the tool which supports the packing cord preparatory to driving it into place and which also constitutes at its free end a guide or support for properly locating the tool with relation to the work it is to perform. Fig. 6 is a cross sectional view taken on the line 45 X—X Fig. 5 and as seen looking thereof from left to right in the direction of the arrows. Fig. 7 is an end elevational view of Fig. 8 as seen looking thereof from left to right. Fig. 8 is a side elevational view 50 of the automatic operative power impelled portions of the tool, the same illustrating also in broken sectional view the manner of controlling the motive parts by a motive agent, such as air or steam. Fig. 9 is an

end elevational view as seen looking at Fig. 8 from right to left in the direction of the arrows.

Referring to Fig. 2, 1 represents one of a pair of tube sheets and 2 one end of a single tube, the opposite ends of which are secured 60 to such tube sheets in the manner shown, there being provided, as is well known by those skilled in the art of steam power plants, the usual enlarged screw-threaded hole adapted to receive, when the tube 2 is 65 in the position shown, the packing cord 3. This packing is ordinarily in the nature of tarred or other water-proofed strands or cords of fibrous material, such as cotton, and in practice the packing thereof is effected 70 after the tubes are secured at their opposite ends in the tube sheets by firmly packing it with a manual packing tool, after which each tube is surrounded with a hollow screw-threaded set-nut 4 turned firmly home 75 through the agency of a screw-driver. This process of packing between the ends of the tubes and the tube sheets is necessarily very tedious when manually effected, and as often there are hundreds of such packings to be 80 effected much time is consumed. My invention, therefore, is designed to effect this packing much more rapidly and effectually, and also to more firmly amass the packing than has heretofore been possible by the well known hand process.

For a full and clear understanding of my invention, such as will enable others skilled in the art to construct and use the same, reference is now had to the drawings 90 in detail, and particularly to Fig. 1, in which 5 represents the breech or body part of the tool which is integral with the handle 6, 7 being a barrel, having vent holes *v*, *v*, *v*, and 8 a diminished end, such parts being 95 secured together by screw-threads as shown, the whole structure simulating a pistol in appearance. 9 represents a tubular reciprocating plunger provided with a piston 10 which fits accurately within the barrel 7. 100 11 represents a guide-tube enlarged at its outer end so as to constitute a guide-way for the reciprocating plunger 9, said guide-tube being screw-threaded and secured in corresponding screw-threads in the breech 105 5, as shown. 12 represents a rotary shaft which fits accurately within the inner surface of the guide-tube 11 and is provided

with an enlarged journal bearing at its outer end, said tube being further enlarged at 13 so as to leave a sufficient space between it and the diminished end 8 of the barrel to constitute a guide-way for the plunger 9. The end of this enlarged part 13 is turned down into the form of a frustum of a cone, as indicated at 14, and is provided with a shoulder 18 adapted to fit accurately against the end of the tube around which the packing is to be inserted. This enlarged part 13 also constitutes a barrel or cylinder around which the packing cord 3 is wound before the tool is put in use, and for the purpose of securing this cord there is provided a longitudinal groove in the body part 13 in which is pivoted upon a pin 16 a longitudinal finger 15 grooved at its outer end, as shown in Figs. 5 and 6, and provided with a spiral spring 17 inserted in a boring in the part 13, the arrangement being such that normally this finger 15 is held at its outer end against the inner face of the diminished end 8 of the barrel. 19 is a spiral spring the function of which is to return the reciprocating plunger to its normal position after it has been actuated by the motive agent, as gas. 20 is a longitudinal slot through the diminished end of the barrel, said slot constituting an opening for the insertion of the cord 3 which is to constitute the packing. 21 represents an opening from the bottom of the handle to the body of the barrel where it is divided into two channels 21¹, 21², the former adapted to convey the propelling source of energy, as air, to the piston 10, and the latter to a driving motor as will be described later on. 22 is a valve held in seated position by a spiral spring 23, said valve and spring being secured in position by a screw 24. 25 is a hollow valve operating plunger normally held in its outward position with the valve seated against the fulcrumed portion of a trigger 26, secured upon a pivot pin 27 and provided with a shoulder which normally permits it, the trigger, to be held in the position shown in Fig. 1. 28 is the operative part of a rotary motor 29 secured to the rear end of the breech and having its shaft 30 connected directly to the rotary shaft 12, 31 being a detachable cap secured to the case of the motor and provided with the necessary journal bearing, as shown. 32 is a pinion carried by the shaft 30, and 33 is a gear-wheel meshing therewith and adapted to rotate upon a journal bearing 34 secured to the breech 5, 35 being another pinion carried by a shaft integral with the gear-wheel 33 and meshing with a second gear-wheel 36 secured to the rotary shaft 12. 37 is a valve seated, under pressure of spring 38, in the channel 21¹ running to the rotary part 28 of the motor 29, and 39 is a valve operated lever operatively connected

with and adapted to lift the valve 37 under thumb pressure. 40, 40 are air vents for liberating the air after it has passed through or acted upon the rotary part 28 of the motor 29.

The operation is as follows—In order to secure the packing cord 3 in the tool, one end thereof is inserted at the outer end of the slot 20 (see Fig. 4) so that it is forced into sufficient frictional relation between it and the inner surface of the diminished end 8 of the barrel to be carried with it on rotation of the shaft 12, thus winding it firmly around 13. A source of power, as steam or air under pressure—preferably the latter—is operatively connected with the opening 21 and the operator then with his thumb presses the valve lever 39, thus allowing the air to pass inward through the opening 21, channel 21¹ to the rotary part 28 of the motor 29, rotating it and hence through the shafts 30 and 12 imparting rotation to the enlarged part 13 of said shaft 12, thereby drawing the cord through the opening 20 and winding it around such enlarged part until the desired amount of cord, which is usually cut in proper lengths, has been completely drawn therearound and is in position to be operated upon by the reciprocating plunger 9. The operator then liberates the valve 37 and allows it to be seated, after which he inserts the coned end 14 of the tool into the end of the tube 2 in the manner shown in Fig. 1 and then operates the trigger 26 successively a number of times until the cord has been driven firmly home, the number of blows given depending upon the density he desires to give to the packing, as will be readily understood by those skilled in the art. The tool is then removed and the set-nut 4 secured in position in the usual manner. In this way the operator passes from tube to tube and very quickly effects such packing and by reason of the reciprocating or hammer-like action of the plunger 9 he is enabled to more effectually pack the material than was possible by hand; or with rotary actuated devices such as have heretofore been devised.

I do not limit my invention to the specific details of construction shown in the drawings, as obviously a number of the features thereof might be departed from and still come within the scope of my claims hereinafter made. Nor do I limit myself to the use of a cord as the packing agent, as obviously I may use a treated flexible fabric and wind the same in position to be driven by the reciprocating plunger; or, I may utilize tubular sections of fabric or analogous packing which may be slipped into position in the tool by forcing the same endwise over the packing support, as for instance, tubular lamp wicks of proper diameter cut into sections of the desired length.

Having thus described my invention what I claim and desire to secure by Letters Patent of the United States is—

1. As an article of manufacture a packing tool provided with means for supporting a packing cord; means for winding the same around the support; a motor for rotating said winding means, and additional means for driving the cord into its final packed position.
2. As an article of manufacture a packing tool embracing a cylindrical barrel and a tubular cord support located therein, said barrel being provided with a slot and the cord support with means for holding one end of the cord; together with additional means for winding the cord around the support and drawing it through the slot, and a motive device for driving said winding means.
3. As an article of manufacture a packing tool embracing a cylindrical barrel and a tubular cord support located therein, said barrel being provided with a slot and the cord support with means for holding one end of the cord; together with power impelled means for winding the cord around the support and drawing it through the slot, and power impelled means for driving the cord into its final packed position.
4. As an article of manufacture a packing tool provided with a tubular packing cord support; power impelled mechanism for

winding the cord around the support, and independent power impelled mechanism for forcing the cord off of the support and into position when it is designed to be used; together with independent controlling means for utilizing the same source of power to drive either the winding mechanism or the packing mechanism.

5. As an article of manufacture a packing tool provided with a tubular packing cord support; power impelled mechanism for winding the cord around the support, and power impelled mechanism for forcing the cord off of the support and into position when it is desired to be used; together with manually controlled means for regulating the application of power to the same.

6. As an article of manufacture a packing tool embracing a tubular cylindrical cord retaining chamber, provided with a cylindrical support concentric with the inner wall of the chamber; in combination with a reciprocating plunger and a manually controlled motive device for regulating the application of power to the plunger.

In testimony whereof I have signed my name to this specification in the presence of two subscribing witnesses.

EDWARD P. STRODE.
